UNITED STATES PATENT OFFICE.

EDWARD A. LANGENBACH, OF CANTON, OHIO.

DESIGN FOR A METALLIC BORDER-PLATE.

SPECIFICATION forming part of Design No. 26,447, dated December 22, 1896.

Application filed November 9, 1896. Serial No. 611,572. Term of patent 7 years.

To all whom it may concern:

Be it known that I, EDWARD A. LANGENBACH, a citizen of the United States, and a resident of Canton, county of Stark, State of Ohio, have invented a new and useful Design 5 for Metallic Border-Plates, of which the following is a full, clear, and exact description, reference being had to the accompanying drawings, making part of this specification.

10 My invention relates to a new design for metallic ceiling-borders; and it consists of a border and a corner-piece therefor of the configuration and ornamentation shown in the accompanying drawings, in which—

15 Figure 1 is a view in elevation illustrating a portion of the body of the border. Fig. 2 is a vertical sectional view on line $x-x$, Fig. 1. Fig. 3 is a view in elevation of my new corner-piece for the border proper; and Fig. 4, a 20 sectional view on line yy , Fig. 3.

25 The leading feature of my design consists of the body A of the border and the corner-piece B therefor, of the configuration and ornamentation shown in the accompanying drawings, which I will now proceed to describe.

30 The body portion of the border has a series of rolls 1, 2, and 3, the central portion a flat field 4, and the lower portion a concaved surface 5, the lower edge of which extends outwardly and lies in the same plane as the field

35 4. The extreme upper edge has circular and elongated beads 6 and 7, respectively, below which, on the outer face of the inward roll 1, is ornamental work, consisting of V-shaped lines 8, inclosing angular figures 9. Below is a horizontal row of leaf-shaped figures 10. Elongated and circular beads 11 and 12, respectively, exact counterparts of those above 40 described, are formed below the leaf-like figures 10, and below these beads 11 and 12 in the inward roll 3 are a series of united curved lines 13, partially surrounding a horizontal

row of inverted-U-shaped figures. Below these figures is the flat field 4, ornamented by 45 the columns or pillars 14, surmounted by urns 15, projecting into a field 16, ornamented by a multiplicity of short irregularly-extending lines inclosed by figures 13 at the top, and a series of circles 18, arranged in curved grooves 50 17. Below the columns or pillars in the roll 5 is a row of leaf-shaped figures 19, and below these figures are alternating series of circular and elongated beads 20 and 21, respectively.

55 The corner-piece forming part of the border in general appearance is substantially the same as the body of the border and nicely matches the same. The corner-piece, like the body portion of the border, has the rolls 1, 2, and 3, the latter roll, however, being curved 60 instead of horizontal to produce the approximately triangular field 22, having the leaf-shaped figure 23. These rolls are provided with the same ornamentation as those shown in Fig. 1 of the drawings. The lower leaf-like 65 figures are the same as those indicated by 19 in Fig. 1, and instead of being arranged in a horizontal row are arranged in a circle, from which extend radially the urn-capped pillars or columns.

70 A design for ceilings thus ornamented gives to the room where employed a neat and pleasant effect and materially adds to the appearance of the surroundings.

75 What I claim is—

1. The design for a metallic border for ceilings as herein shown and described.
2. In the design for a metallic border, the corner-piece, as herein shown and described.

80 In testimony whereof I have hereunto set my hand this 28th day of October, A. D. 1896.

EDWARD A. LANGENBACH.
